199,010

PELLET IMPLANTER FOR ANIMALS AND THE LIKE

Lawrence De Rome, Silver Lake, Wis. (Bassett, Wis.)

Filed May 13, 1963, Ser. No. 74,861

Term of patent 14 years

(Cl. D83—12)

FIGURE 1 is a top perspective view of a pellet planter for animals and the like showing my new design; FIGURE 2 is an enlarged end view thereof; and

FIGURES 3, 4, and 5 are side elevations thereof, which are partially shown for convenience of illustration.

I claim:

The ornamental design for a pellet planter for animals and the like, as shown and described.

UNITED STATES PATENT OFFICE
CERTIFICATE OF CORRECTION

Design No. 199,010

August 25, 1964

Lawrence De Rome

It is hereby certified that error appears in the above numbered patent requiring correction and that the said Letters Patent should read as corrected below.

In the grant, lines 1 to 3, for "Lawrence De Rome, of Silver Lake, Wisconsin," read -- Lawrence De Rome, of Silver Lake, Wisconsin, assignor, by mesne assignments, of one-third to Gerald T. Dobie and two-thirds to Carl F. Jensen, both of Chicago, Illinois, --; line 13, for "Lawrence De Rome, his heirs" read -- Gerald T. Dobie and Carl F. Jensen, their heirs --; in the heading to the drawing and printed specification, line 4, for "Lawrence De Rome, Silver Lake, Wis. (Bassett, Wis.)" read -- Lawrence De Rome, Silver Lake, Wis., assignor, by mesne assignments, of one-third to Gerald T. Dobie and two-thirds to Carl F. Jensen, both of Chicago, Ill. --.

Signed and sealed this 22nd day of December 1964.
